(57) **CLAIM**

The ornamental design for a coffee pod drawer as shown and described.

DESCRIPTION

FIG. 1 is a front perspective view of a coffee pod drawer showing the claimed design;

FIG. 2 is another front perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is another perspective view in which the bottom of the coffee pod drawer is in an open configuration; and, FIG. 10 is an enlarged detail view of area 10 shown in FIG. 1.

The dot-dash broken lines represent the designation of an enlarged view and form no part of the claim design.

1 Claim, 10 Drawing Sheets
